(57) **CLAIM**

The ornamental design for an apparatus for recording, transmitting and/or processing information, as shown and described.

DESCRIPTION

FIG. 1 is a perspective view of an apparatus for recording, transmitting and/or processing information;

FIG. 2 is a front view of the apparatus for recording, transmitting and/or processing information, as shown in FIG. 1;

FIG. 3 is a rear view of the apparatus for recording, transmitting and/or processing information, as shown in FIG. 1;

FIG. 4 is a side view of the apparatus for recording, transmitting and/or processing information, as shown in FIG. 1;

FIG. 5 is a side view, opposite the side view shown in FIG. 4, of the apparatus for recording, transmitting and/or processing information, as shown in FIG. 1;

FIG. 6 is a top view of the apparatus for recording, transmitting and/or processing information, as shown in FIG. 1; and,

FIG. 7 is a bottom view of the apparatus for recording, transmitting and/or processing information, as shown in FIG. 1.
